LATCH LOCK

George Henry Wheary, Racine, Wis., assignor to
Wheary Trunk Company, Racine, Wis., a corporation of Wisconsin

Application May 14, 1934, Serial No. 725,448

10 Claims. (Cl. 70—2)

This invention relates to improvements in latch locks and refers more particularly to locking devices for luggage.

It is an object of this invention to provide a latch lock which is simple and rugged in construction and affords a neat external appearance.

Another object of this invention is to provide novel means for mounting the spring for yieldingly urging the sections apart upon disengagement of the latch bolt from its keeper recess.

Another object of this invention is to provide novel means for mounting the latch bolt and locking the same against actuation to its inoperative position.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a perspective view illustrating a portion of a wardrobe suit case equipped with the latch lock of this invention;

Figure 2 is a view of the back of the latch lock detached from the suit case and with a portion thereof broken away to illustrate structural details;

Figure 3 is a vertical section view through the latch lock taken substantially on the plane of the line 3—3 of Figure 2;

Figure 4 is a perspective view of one of the sections of the latch lock illustrating the formation of the keeper and the spring to yieldingly urge the sections apart; and

Figure 5 is a detail section view taken longitudinally through the lock mechanism on the plane of the line 5—5 of Figure 2 and illustrating particularly the manner in which the latch releasing means is secured against actuation.

Referring now more particularly to the accompanying drawing, in which like numerals indicate like parts throughout the several views, the numerals 5 and 6 designate the two sections or parts of a suit case or similar luggage which are to be secured together by the latch lock.

The latch lock of this invention comprises two sections 7 and 8 attached respectively to the suit case parts 5 and 6 as illustrated. Both sections 7 and 8 have covers or housings 9 and 10 respectively, stamped from bendable metal with their medial portions pressed outwardly to provide cavities in which the mechanism of the latch lock is assembled.

The section 7 carries the latch bolt 11 which is confined between the outer wall 12 of the cover or housing 9 and a metal plate 13 secured to the back thereof by hollow rivets 14. The hollow rivets 14 are preferably integral upset portions of the cover, and being hollow, provide the apertures through which the fastenings 15 pass to secure the section to the suit case part 5.

The metal plate 13 is substantially T shaped as illustrated in Figure 2, and at opposite sides of its stem, spaced lugs 16 project inwardly toward the cover wall 12 to receive trunnions 17 extended outwardly from the adjacent legs of the latch bolt 11, which is substantially U shaped. In this manner, the latch bolt is mounted so as to have a limited degree of pivotal movement between the cover wall 12 and the plate 13.

At its upper closed end portion, the latch bolt has two spaced lugs or ears 18 bent laterally therefrom toward the cover wall 12 for engagement with a keeper recess 19 formed in a keeper 20, which is carried by the other section 8, the upper edges of the lugs or ears 18 being curved or inclined to facilitate the engagement thereof with the keeper recess. The specific construction of the keeper will be hereinafter more fully described.

Fixed to the latch bolt is a hollow push button 21 to project through an opening in the cover wall 12 and afford means whereby the latch bolt may be pushed inwardly and disengaged from its keeper recess.

A spring 22 confined between the bottom of the hollow push button and the plate 13 yieldingly opposes inward depression of the latch bolt and yieldingly maintains the latch bolt engaged with its keeper recess.

Disposed between the legs of the U shaped latch bolt and confined between the cover wall 12 and the plate 13 is a key controlled locking mechanism designated generally by the numeral 23. This locking mechanism may be of any suitable construction and in the present instance embodies a plurality of tumblers 24, one of which is movable to a position indicated in dotted lines 25, disposed between the closed upper end of the pivoted latch bolt and the plate 13 to positively

preclude inward depression of the latch bolt and thereby secure the latch bolt in its position engaged with the keeper recess.

The lock mechanism includes a cylinder 26 exposed on the outer face of the cover wall 12 for the reception of a key 27 through which the tumblers are actuated to effect the movement of the locking tumbler to and from its operative bolt securing position. The specific construction of 10 the lock mechanism, however, forms no part of this invention and is therefore not shown in detail.

It is to be observed that the entire latch bolt and its operating mechanism are confined within 15 in the hollow of the cover 12 which, as stated, is open at its back and is closed at all sides so that the cover affords a convenient and neat housing for the latch bolt and its operating mechanism. The side wall 30, which abuts the side wall 31 of 20 the cover 10 of section 8, is apertured as at 32 to permit the projection of the keeper 29 into the cover or housing 12 for engagement with the latch bolt.

The side wall 30 also affords a rigid abutment 25 against which a spring 33 carried by the section 8 engages to yieldingly urge the sections apart and automatically separate the same upon disengagement of the latch bolt from its keeper recess.

30 The keeper 29 is formed by a tongue integral with a reinforcing plate 34 secured in the hollow of the cover 10 also by hollow rivets 14, which, as stated, may be part of the cover and being hollow, provide means through which the fastenings 35 15 pass to secure the section 8 to the suit case part 6.

The reinforcing plate is formed of hardened metal and as best illustrated in Figure 4, has a central slit or opening 35 substantially dividing 40 the same into two portions 36 and 37. The portion 37 is depressed or offset with respect to the portion 36 to lie directly adjacent the outermost wall 38 of the cover 10, which as seen in Figure 3, occupies the same plane as the cover wall 12 of 45 the section 7. The tongue forming the keeper 29 projects from this portion 37 through an opening 39 cut in the side wall 31.

A pin 40 carried by the portion 37 of the reinforcing plate, has the looped or closed end 41 of the spring 33 engaged thereover. This spring 50 is substantially of hairpin shape with one leg 42 thereof engaging the edge 43 of the opening or slit 35 and its other leg 44 curved outwardly to project through the opening 39 for engagement with 55 the side wall 30 of section 7, and with the extremity of its leg 44 arranged to abut the side wall 31 to limit outward projection of the leg 44, as will be readily apparent.

It is to be observed that the extremity of the 60 leg 42 is cut off at an angle as at 45 with the point of the angle innermost so that the normal spring tension acting through the angularity of the cut end 45, serves to retain this end of the spring in engagement with the edge 43.

65 From the foregoing description taken in connection with the accompanying drawing, it will be readily apparent to those skilled in the art to which this invention appertains, that the latch lock of this invention is of simple and rugged construction and that it provides an exceptionally neat external appearance.

What I claim as my invention is:

1. In a latch lock of the character described, two complementary sections adapted to be attached to two parts to be secured together, said

sections having stamped metal covers arranged to abut each other, a spring carried by one section and engageable with the other to yieldingly urge the sections apart, a latch bolt disposed within the stamped cover of one section, and a keeper carried by the other section for engagement with the latch bolt to hold the sections together against the action of said spring, said keeper being an integral part of a hardened metal plate secured in the cover of said other section, 10 and having parts thereof on different planes so as to afford a shoulder against which the spring abuts.

2. In a latch lock of the character described, complementary sections adapted to be attached to two parts to be secured together, stamped metal housings for the sections adapted to abut, a latch bolt disposed within the housing of one section, a keeper carried by the other section and arranged to enter the housing of the first section 20 for engagement with the latch bolt, said keeper being an apertured tongue integral with and extending from a reinforcing plate secured in the housing of said other section, and a spring carried by said reinforcing plate to engage the 25 first designated section as the sections approach each other to yieldingly oppose movement together and thereby automatically spread the sections apart upon release of the latch bolt from its keeper recess.

3. In a latch lock of the character described, two complementary sections adapted for attachment to two parts to be secured together, each of said sections having a stamped cover formed with a hollow cavity, a metal plate secured to 35 the inner face of one section over its hollow cavity, a latch bolt pivotally mounted from said metal plate and disposed between said metal plate and the cover, spring means to yieldingly urge the latch bolt forwardly toward the cover, 40 means on said latch bolt projecting through the cover for depressing the latch bolt against the action of its spring means to an inoperative position, lock mechanism confined between said metal plate and the cover and operable from the exterior of the cover to secure the latch bolt against actuation to its operative position, and a keeper carried by the other section and adapted to enter the cavity of the first section for operative engagement with the latch bolt.

4. In a latch lock of the character described, two sections adapted for attachment to two parts to be secured together, a latch bolt carried by one section, a keeper carried by the other section and engageable with the latch bolt, said other section having a hollow housing open at its back and closed on all sides, a reinforcing plate fixed to said hollow housing with portions thereof on different planes to define a shoulder, a tongue integral with said reinforcing plate and projecting through an opening in one side wall of the cover, said tongue being apertured to provide a keeper for the latch, and a spring carried by said reinforcing plate with a portion thereof bearing against the shoulder and another portion projecting through said opening in the side wall of the cover for engagement with the first designated section.

5. In a latch lock of the character described, two sections adapted to be attached to two parts 70 to be secured together, a latch bolt carried by one section, a keeper carried by the other section and engageable with the latch bolt, said other section comprising a cover having a cavity with a 75 opening through one side wall thereof, a rein-

forcing plate secured in said cover with portions thereof on different planes to define a shoulder and having a tongue projecting integrally therefrom through said opening, said tongue being

- 5 apertured to form the keeper, and a substantially hairpin-shaped spring having one leg bearing against said shoulder and its other leg curved to project through the opening for engagement with the other section and its extremity engageable 10 with the cover adjacent said opening to limit the outward projection thereof.

6. In a latch lock of the character described, two sections adapted to be attached to two parts to be secured together, a latch bolt carried by one 15 section and a keeper carried by the other section, said keeper being an apertured projection on a hardened metal reinforcing plate secured in said other section, said hardened metal reinforcing plate having a central opening to divide the same 20 generally into two portions which are offset with respect to each other so that one edge of said central opening provides a shoulder, and a spring having a part bearing against said shoulder and engageable with the other section to yieldingly 25 urge the sections apart.

7. In a latch lock of the character described, two sections adapted to be attached to two parts to be secured together, a latch bolt carried by one section and a keeper carried by the other section and engageable with the latch bolt, said keeper being an apertured tongue projecting from a hardened metal reinforcing plate secured to 30 said other section, said reinforcing plate having a central opening dividing the reinforcing plate 35 substantially into two portions and the plate being offset so that its two portions lie in different planes and the edges of the central opening afford well defined abutments, a pin carried by the reinforcing plate, and a substantially hairpin-shaped 40 spring having its closed end engaged over said pin and having the extremity of one leg bearing against the abutment formed by one edge of the central opening and its other leg curved to project from the adjacent wall of said other 45 section for engagement with the first designated section to yieldingly urge the sections apart.

8. In a latch lock of the character described, two complementary sections adapted to be attached to two parts to be secured together, a latch bolt carried by one section and a keeper carried by the other section, said other section comprising a stamped metal cover formed with a cavity open at its back and closed at all sides with the side wall facing the first designated section provided 55 with an opening through which the keeper projects for extension into the first designated sec-

tion, said keeper being an apertured tongue integral with and projecting from a hardened metal reinforcing plate secured in said cover, said reinforcing plate having a central slit and being offset at opposite sides of said slit to provide portions on different planes and whereby the edges of said slit form well defined shoulders, the apertured tongue providing the keeper extending from the portion of the reinforcing plate nearest the bottom of the cavity in the cover, and a spring 10 projecting through the opening in said cover side wall and overlying the apertured tongue for engagement with the first designated section to yieldingly spread the sections apart upon release of the latch bolt from the keeper. 15

9. In a latch bolt of the character described, two complementary sections adapted to be attached to two parts to be secured together, one of said sections having a keeper projecting therefrom for extension into the other section, said other section being stamped of bendable metal and provided with a hollow cavity, a metal plate closing said hollow cavity at the rear of the cover, a latch bolt pivoted from said metal plate with a part engageable with the keeper as the sections are 20 brought together, spring means confined between the pivoted latch bolt and said metal plate to yieldingly urge the latch bolt to its operative position, a button carried by the latch bolt and projecting through an opening in the cover, 25 whereby the latch bolt may be depressed against the action of its spring means to disengage the same from the keeper, and lock means confined between said metal plate and the cover and operable from the exterior of the cover to secure 30 the latch bolt against movement to its inoperative position. 35

10. In a latch lock of the character described, two complementary sections adapted to be attached to two parts to be secured together, a latch bolt carried by one section, a keeper carried by the other section and engageable with the latch bolt, and a spring carried by one section and engageable with the other section to yieldingly urge the sections apart, said spring being substantially 40 hairpin-shaped with one leg thereof curved outwardly for engagement with the abutting portion of the adjacent section and its other leg engaging a shoulder on the section carrying the spring, the extremity of said other leg being cut at an angle with its point innermost so that the tension 45 of the spring acting through the angle of the cut end of said leg tends to retain said leg engaged with said shoulder. 50

GEORGE HENRY WHEARY. 55
